UNITED STATES PATENT OFFICE.

RAOUL BERNAT, OF BORDEAUX, FRANCE.

PNEUMATIC JACK.

Application filed December 9, 1921. Serial No. 521,216.

To all whom it may concern:

Be it known that I, RAOUL BERNAT, citizen of the Republic of France, residing at Bordeaux, France, 6 Rue des Douves, have 5 invented a new Pneumatic Jack, of which the following is a specification.

This invention relates to a pneumatic jack having a piston packed by the action of an appropriate fluid under pressure and so arranged 10 that the pressure of the compressed air sent into the apparatus acts both to produce the raising of the piston, fast with the head of the jack, and to ensure, in a perfect and continuous manner, the tightness of the 15 joint between the piston and the cylinder in which it moves. This pneumatic jack which is shown, by way of example, in sectional elevation in the annexed drawing is constituted as follows:

20 It comprises a cylinder (1) provided with a bottom (2) and closed by a cover (3). Within this cylinder a piston made in two parts 4', 4'' is free to move, and between these parts is arranged a piece (5), whose 25 straight section is that of a double T, and which is provided with an opening (6). This piece (5) serves to hold against the internal face of the parts 4' and 4'' of the piston, two cup leathers 7 and 8, while leaving 30 a free space between them designed to form the joint between the cylinder and the piston. The two parts of this latter are screwed to the lower part of a tube (9) forming the lifting-bar of the jack and provided 35 with openings (10) ensuring communication between the interior of the piston and the interior of the cylinder (9). The upper part of this latter is so formed as to constitute the head (11) of the jack.

40 The cover (3) may be furnished with a packing (12) forming a guide for the lifting-bar of the jack, and with an air hole enabling the air to escape as fast as the piston rises in the cylinder (1). These two elements, however, are not indispensable, the 45 guiding of the lifting-bar of the jack having no need to be air-tight so permitting the escape of this latter during the progressive rise of the piston in the cylinder.

50 On the lower internal part of the tube (9) is furthermore screwed the base of a tube (14) open at its upper end.

Another tube (15), arranged within the tube (14), and whose upper open end is 55 situated above that of this latter, as high up as possible in the inside of the tube (9),

is furthermore fitted to the bottom (2) of the cylinder (1) by means of a piece (16) screwed on to this bottom. This piece comprises an interior passage (17), (18), enabling the tube (15) to be placed into communication with a flexible tube (19), mounted, at (20), on a nipple or socket of the said piece. This flexible tube pipe carries an obturating device or valve (21), similar to that of the inner tube of a pneumatic tyre, connected by its adutage (22) to an air pump, an ordinary pump for pneumatic tyres or any reservoir of compressed air, a Michelin flask for instance.

The direction of the working of this obturating device must be such that any return of air towards the pump or the reservoir of compressed air is impossible.

The entire apparatus is mounted on a suitable support (23).

The free space on the interior of the piston, and the annular space comprised between the two tubes (9) and (14), are filled with a liquid, such as glycerine, oil, or water, or with a semi-fluid body, such as the solder of curriers; this liquid, or this semi-fluid body, rises to the upper part of the tube (9), and is capable of coming into contact with inner walls of the cylinder (1) by flowing through the space existing between the two cup leathers (7) and (8).

To introduce the aforesaid fluid or semi-fluid body into the apparatus, it is poured through the air hole (13), (when there is one) and then this hole is closed. The piston is then drawn towards the top of its cylinder by means of its lifting-bar (9), which has the effect of slightly driving cup leathers 7 and 8, due to the movement of the piston, towards the interior of the hollow space of the piston, since there is no pressure within the piston to press the leathers 7 and 8 against the wall of casing 1. The liquid accordingly passes between the leathers and 100 wall of casing 1 and into the interior of the piston, as well as into the space between the tubes 9 and 14.

In the case where the apparatus has no air hole, the filling is effected by forcing the 105 liquid, or semi-fluid body, through the tube (15).

In these conditions of setting up, the apparatus will work in the following manner:

In the working of the rise, the air hole 110 (13) is opened (when the apparatus is provided with one) then air under pressure is

sent into the apparatus; this air escapes at the lower part of the tube (15), by following the path shown by the arrows α^1 , α^2 and α^3 , and exerts its pressure, on the one hand, 5 on the free surface of the liquid contained between the tubes (9) and (14), and on the other hand by descending between the tubes (14) and (15) on to the lower face of the piston on which it thus produces the rise, 10 and hence that of the lifting-bar and of the head of the jack.

The pressure of the air on the liquid, or semi-fluid body, contained in the apparatus, 15 has the effect of strongly pressing the cup leathers (7) and (8) against the inner walls of the cylinder (1), so ensuring in a perfect way, the tightness of the joint between the piston and the cylinder, and this in a constant manner as the mass of the aforesaid 20 body follows all the movements of the piston.

For working the fall, the controlling rod with which the obturating device (21) is 25 furnished, is pressed down, the air is then driven out more or less quickly and the object raised by the jack descends with a speed corresponding to that of the flow of the air. A certain pressure from the compressed air 30 remains in the device as long as the piston is not at its lowest point, and leathers 7 and 8 are constantly forced against the cylinder 1 for making a tight packing.

In all its various movements, the fluid contained in the piston and between tubes 9 35 and 14 is not displaced, and serves only to force the packing leathers 7 and 8 against the wall of cylinder 1 under the pressure of compressed air in the interior of the device.

40 After the working, the air hole, (should there be one) is closed.

The above described arrangement may of course comprise various modifications in its construction without departing from the spirit of the invention.

Having now particularly described the nature of the said invention and in what manner the same is to be performed, I declare that what I claim is:

1. A pneumatic jack comprising a casing, 50 a hollow piston in said casing, flexible gaskets positioned between the piston and casing, said hollow piston being formed to receive a fluid, means for supplying pressure fluid to the lower face of the piston, means 55 for supplying fluid to the hollow piston, and means for permitting the pressure of the fluid supplied to the lower face of the piston, to be exerted in the hollow piston, whereby to pack the gaskets against the casing.

2. A pneumatic jack according to claim 1, 60 said hollow piston carrying two spaced concentric tubes, the space between the concentric tubes being formed to receive a fluid and being in communication with the hollow 65 piston.

3. A pneumatic jack according to claim 1, 70 the means for supplying pressure fluid to the lower face of the piston, comprising a tube carried by the piston.

4. A pneumatic jack according to claim 2, 75 the means for supplying pressure fluid to the lower face of the piston, comprising a tube carried by the piston.

In testimony whereof, I have signed my 76 name to this specification in presence of two subscribing witnesses.

RAOUL BERNAT.
